UNITED STATES PATENT OFFICE.

W. V. GEE, OF NEW HAVEN, CONNECTICUT, ASSIGNOR TO THE ATWATER & BRISTOL
MAN'G COMP'Y.

LOOM.

Specification forming part of Letters Patent No. 12,457, dated February 27, 1855; Reissued
September 15, 1857, No. 494.

To all whom it may concern:

Be it known that I, WILLIAM V. GEE, of New Haven, in the State of Connecticut, have invented certain Improvements in Weaving-Looms for Forming Buttonholes in the Process of Weaving Webbing and other Fabrics, of which the following is a full, clear, and exact description, reference being had to the accompanying drawings, 10 making part of this specification, in which—

Figure 1, is a back elevation with certain parts of the frame work removed to exhibit portions of the mechanism. Fig. 2, a side elevation. Figs. 3 and 4, are sections taken 15 at the lines *A*, *a*, of Fig. 1, and *B*, *b*, of Fig. 2. Fig. 5, an edge view of the cam barrel *x*; and Fig. 6 a plan view of the beam *k', k'*, and the levers *l', l'*.

The same letters indicate like parts in all 20 the figures.

The object of my invention is to form button holes in suspender webbing or other fabric to be woven, and by the process or operation of weaving, leaving a selvage on 25 each edge of the button holes in the same manner as on the edges of the webbing or fabric. And my said invention consists in combining with the loom, two or more sets of harness so arranged that all the warps 30 on one side of the button hole to be formed shall be controlled by one set of leaves of harness, and the warps on the other side of the button hole controlled by another set of leaves of harness, and in that order for 35 any other number of button holes to be made in the breadth of the fabric, the number of leaves of harness in each set being governed by the kind of fabric to be woven, and so that the two or more sets of harness may be 40 operated together as one set in weaving the fabric where button holes are not to be formed, and where a button hole is to be formed, one set of harness shall be lifted up and suspended in their operation, that the 45 shuttle may pass under that portion of the warps and weave the fabric with a selvage on each side of the length required for a button hole, and when that is completed that set of harness is left up and suspended, and 50 the other portion let down to weave the portion of fabric on the other side of the button hole with a selvage on each edge, and so on for any other number of button holes, and after the required number of picks, 55 that the whole may be put in action to

weave the entire breadth of fabric, thereby uniting the two parts of the fabric and leaving a button hole or holes of any required length properly united at both ends and with a selvage on each edge. And my 60 said invention also consists in connecting all the leaves of harness that constitute one set, under the before named arrangement, with one rod or slide, or the equivalent thereof, controlled by a treadle or lever operated by a cam, so that at the required time either part of the harness can be lifted up and thrown out of action or let down and put in action. And finally my said invention 65 consists in combining with the mechanism which lifts up and lets down each set of harness to effect the required change by a quick movement, a cam wheel moving by a slow motion and actuating levers, or the equivalents thereof, to engage or disengage 70 the lifting apparatus and either suspend or set in action any required portion of the harness, by which combination the length of the button holes, and the number and distance between them in any given 75 length of webb can be determined by the slow moving cam wheel, while the shifting can be effected by cams which move with a rapid motion to effect the change of the harness between the picks of the loom. 80

In the accompanying drawings *a*, represents the frame, and other appendages of a loom, such as is usually employed for weaving suspender webbing, in which several webs can be woven side by side; the lathe *b*, being provided with a number of reeds and each reed with a shuttle *c*, having a range of motion adapted to the width of the fabric. The mechanism for operating the lathe, for delivering the warps, taking up 90 the woven fabric, driving the shuttle, &c., being constructed and operating in manner well known to weavers, and not necessary here to be described as they make no part of my invention. The harness is operated 95 in the usual manner by a series of treadles *d*, actuated by cams *d'*, on the cam shaft *e*, in the usual manner. The ends of these treadles are connected with levers *f*, mounted at right angles to the line of the treadles, 100 and these are in turn connected with the inner ends of two double sets of levers *g, g'*, and *g', g'*, to the outer ends of which the several leaves of harness *n*, are suspended 105 by wires *i*, or by cords. The treadle frames 110

descend by their weight, or can be drawn down by springs j , or weights, if preferred, and they are drawn up when required by the action of the cams d' , on the treadles and their connections with the levers to which the harness leaves are suspended.

The harness is divided into two sets, one half suspended to the lower set of levers g, g , and the other half to the upper set of levers g', g' , and each set must be complete in itself and the number of leaves in each set depending upon the fabric to be woven, and therefore to be determined in mounting the loom. One half of the warp threads for each web are passed through the mails of one set of harness, and the other half through the mails of the other set, so that each set can weave a complete web of a given width, or both sets may weave a web of double that width. The one set of treadles actuates both sets of harness; but if one set be lifted and kept up then they will only actuate the other set. When weaving the fabric or web of the entire width both sets of harness are kept in action; but when a button hole is to be formed the action of one set is suspended and lifted up that the shuttle may pass under the warps governed by it, while weaving the web on the other side of the button hole whatever may be its length, which is effected in the following manner: The two sets of levers g, g , and g', g' , are each set divided into two parts, one part extending from near the middle to the right, and the other to the left. They turn on fulcrum pins i', i' , and i^2, i^2 , and their outer ends rest in stirrups j', j', j^2, j^2 , one at each end and adapted to slide vertically in grooves in the two beams k, k , and k', k' , which inclose the levers. These stirrups are connected each to the outer ends of levers arranged in pairs l, l , and l', l' , one pair for each set of stirrups, the two levers of each pair being connected by a pin on the end of one working in a slot in the other, so that one will work the other. And one of each pair is connected by a rod m , with one of two sliding bars n and n' so that when either of these bars are drawn down the two stirrups connected therewith, in the manner described, will be lifted up, which will in turn lift one set of levers g, g , and g', g' , and thus elevate and suspend the action of one set of harness, while the other continues to operate.

The bars n , and n' , are drawn down by a treadle o , placed by the side of other treadles, and actuated by a cam p , on the end of the cam shaft, there being a corresponding cam and treadle p' , and o' , on the other side to give the action in opposite directions by having the two treadles o, o' , connected by rods with the opposite ends of a balance lever g .

The treadle o , is connected by a joint link

r , with a slide s , which works on ways t, t , and by this connection the slide is made to move up and down at every rotation of the cam shaft. Now the bars n , and n' , carry a spring catch u, u' , and whenever either of these catches is forced toward the slide s , it takes hold of it in its descent and draws down the bar, and as the bar is notched at v , to receive a spring dog w , it is held until the dog is drawn out. In this way the two bars are drawn down to lift up either of the two sets of harness, or liberated to permit the harness to be operated by the treadles. But the time when either set of harness is to be lifted, and liberated, and the length of time that they shall be suspended, and kept in action, is determined by a cam barrel x , with four cam wheels or divisions 1, 2, 3, 4. It receives motion from a worm y , on the cam shaft e , and thence through a train of wheels z, z', z^2 . In this way slow motion is imparted to the cam barrel, and the four divisions are so disposed as to act each on one of four spring levers a', a^2, a^3, a^4 , the first two corresponding with the bars n and n' , so that when a depression of the divisions in the cam barrel passes under either of these two levers, they are permitted to be forced by the tension of their springs and thereby to force in the spring catches u, u' , on the bar n , or n' , so that the slide s , will catch hold of, and thus draw down the appropriate bar which is there held by the spring dog. Now then it follows that the circumference of this cam barrel, its velocity relatively to the other parts of the loom, and the distance between the several depressions in the second and third divisions of the cam barrel, will determine the periods when either of the two bars n and n' , shall be drawn down to suspend the action of either of the two sets of harness. But the other two divisions of the cam barrel determine when the bars shall be liberated to permit the harness to be brought into action, and this is done by the two spring levers a^3 , and a^4 , each of which carries a pin b^2 , which passes through the corresponding dog w , that holds down the bar, and the depressions in these cams permits the levers to descend so that these pins may pass through sufficiently far to be acted upon by a cam formed projection on the slide s , which forces the spring dogs out of, and liberates the bars.

From the foregoing anyone skilled in the art of weaving will be enabled to determine the form of the cam divisions in the cam barrel and the relations of the one to the other to determine the length of the button holes and the distance apart in the length of the web. And it will be obvious that instead of one button hole in the width of the fabric, two or more may be made in the same manner by increasing the number of sets of harness, as for instance, three sets

will be required for two button holes, or in other words the loom must be mounted with one more set of harness than the number of button holes to be formed in the width of fabric.

- 5 The ratchet hand c^2 of the take-up motion is connected by a cord d^2 , with a short lever e^2 , jointed to one of the stirrups j^2 , which controls the first set of harness that is to be 10 lifted up or suspended, so that while the web is woven on one side of the button hole the take-up motion is suspended, the web yielding to the beat of the lay for this purpose. But at the end of this, when the two sets of 15 harness exchange position to weave the web on the other side of the button hole, the take-up motion is set in action, although it may be suspended also, and set in action when the whole width of webbing is being woven.
- 20 It will be obvious to the experienced weaver that the take-up, and delivery motions may be continued in action during the whole time of weaving the web on each side of the button hole, provided they be moved 25 back after weaving the first side and before beginning the second side, and while weaving the second side the web woven on the first side yields in front of the reed at each beat of the lay.
- 30 I wish it to be understood that I do not limit myself to the special construction of the parts and the arrangement of them, as these may be greatly varied by the substitution of mechanical equivalents, but that I

claim the privilege of modifying these so 35 long as I attain the same ends by means substantially the same.

What I claim as my invention and desire to secure by Letters Patent is—

1. The method of forming button holes in 40 the process of weaving suspended webbing and other fabrics by mounting the loom with two or more sets of harness, each governing all the warp threads on one side of the intended button holes, and each set being 45 capable of being lifted and suspended, substantially as and for the purpose set forth.

2. And I also claim, connecting each set 50 of harness, under the before named method of weaving fabrics with button holes, with a bar or slide governed by a cam, and catch or the equivalent thereof, to suspend the operation of either set of harness, substantially as described.

55 3. And I also claim in combination with the before described mechanism for lifting and suspending the action of the sets of harness, or any equivalent thereof, the mechanism for determining the period of 60 the suspension of the action of the several sets of harness, or any equivalent thereof, substantially as and for the purpose specified.

W. V. GEE.
